S. M. RIKER,
CROCHET NEEDLE,
APPLICATION FILED DEC. 29, 1920.

1,409,579.

Patented Mar. 14, 1922.

Inventor:
Samuel M. Riker,
By his Attorneys.
Braentzel and Richards.

UNITED STATES PATENT OFFICE.

SAMUEL M. RIKER, OF CHESTER, NEW JERSEY.

CROCHET NEEDLE.

1,409,579.

Specification of Letters Patent. Patented Mar. 14, 1922.

Application filed December 29, 1920. Serial No. 433,817.

To all whom it may concern:

Be it known that I, SAMUEL M. RIKER, a citizen of the United States, residing at Chester, in the county of Morris and State of New Jersey, have invented certain new and useful Improvements in Crochet Needles; and I do hereby declare the following to be a full, clear, and exact description of the invention, such as will enable others skilled in the art to which it appertains to make and use the same, reference being had to the accompanying drawings, and to characters of reference marked thereon, which form a part of this specification.

15 This invention relates, generally, to improvements in needles, and more especially to crochet-needles; and, the present invention has reference, more particularly, to a novel construction of crochet-needle, the 20 shank or main stem of which is formed with a twist for the reception of the operator's finger, the purpose being to readily and effectively hold and maintain the needle in its proper and operative relation to the hand, 25 as well as to the work.

The present invention, therefore, has for its principal object to provide a novel and simply-constructed crochet-needle provided with an integrally formed finger-receiving 30 loop or guard, with a view of providing a simple means of maintaining the proper position of the needle with relation to the hand of the operator, and also dispensing with the usual tiring effect, due to the fact that the 35 shank or stem of the usual needle has to be firmly held between the thumb and the forefinger, while with the retaining loop or finger-ring arrangement of the present device, the needle, while crocheting is properly held 40 against the forefinger of the operator without the necessity of contact or pressure of the thumb against the needle as heretofore, thus by means of the free movement of the forefinger permitting a free and wider scope 45 of movement of the tip of the needle.

Other objects of the present invention not at this time more particularly enumerated will be clearly understood from the following detailed description of the present invention.

With the various objects of the present invention in view, the said invention consists, primarily, in the novel crochet-needle hereinafter more fully set forth in the following

specification and as embodied in the clauses 55 of the claim which are appended to the said specification.

The invention is illustrated in the accompanying drawings, in which:

Figure 1 is a perspective view of a 60 crochet-needle made according to and embodying the principles of the present invention, said view illustrating in connection with the hand of the operator, the application of the crochet-needle to the forefinger 65 of the hand; Figure 2 is a side elevation of the crochet-needle; and Figure 3 is a transverse sectional representation of the same, said section being taken on line 3—3 in said Figure 2, looking in the direction of the 70 arrow α .

Similar characters of reference are employed in the said above described views, to indicate corresponding parts.

Referring now to the several figures of 75 the drawings, the reference-character 1 indicates the shank or main stem of a crochet-needle, usually made of a continuous piece of tempered-wire, which is formed at its one end-portion with a crocheting tip or point, 80 as 2, of the usual configuration.

Intermediate of the said tip or point 2 and the end-portion 3 of the said shank or stem 1, the latter is made with a spirally shaped twist, as 4, extending, preferably, to 85 one side of the shank or stem, as shown, and which provides a suitable loop or finger-receiving guard, integral with the parts 5 and 6 of the shank or stem, substantially as shown in the several figures of the 90 drawings.

From the foregoing description of the present invention it will be clearly evident that a cheap and simply-constructed crochet-needle has been produced, the finger-receiving 95 loop being of the same cross-section as that of the main shank or stem 1, being readily twisted or bent into the configuration desired, without any undue additional operations of manufacture and also providing a 100 strong attaching means, without unnecessary increase in the cost of manufacture.

Furthermore, the spirally formed and angular arrangement of the receiving loop, with relation to the longitudinally extending 105 longitudinal axis of the main shank or stem 1, is such that the loop serves not only to properly position the crochet-needle in its

position upon the forefinger, relative to the work, but the loop also permits the needle to be used in a swinging or oscillatory manner with relation to the forefinger, so that 5 the needle-point may be variously used upon the work.

The arrangement of the various parts as described in the foregoing specification and as illustrated in the accompanying drawings 10 is extremely simple and efficient, and, furthermore, a crochet-needle is produced which can be readily and conveniently used by the operator, without cramping the hand or the forefinger and thumb of the user, as is so often the case with needles of the usual and common straight shanks or stems, necessitating the holding of the same between the forefinger and thumb.

While in the foregoing I have described 20 my invention as applied to the shank or stem of a crochet-needle, still I am aware that the principles of the present invention may be applied to shanks or stems of the various kinds adapted for use to numerous 25 purposes other than crochet-work. Hence, I do not wish to be understood as limiting

my present invention solely in connection with the shank or stem of a crochet-needle.

I claim:

1. A continuous shank or stem adapted 30 for use as a crochet-needle, or the like, said shank being provided at one end with a work-point, and said shank being formed intermediate of its ends with a spirally formed finger-receiving loop integral with 35 and extending angularly to the longitudinally extending axis of the shank at one side of the shank.

2. A crochet-needle comprising a shank and a ring-shaped finger-receiving loop, all 40 made in a continuous piece of wire, said loop being spirally formed and extending angularly to the longitudinally extending axis of the shank at one side of the shank.

In testimony, that I claim the invention 45 set forth above I have hereunto set my hand this 23rd day of Dec. 1920.

SAMUEL M. RIKER.
